United States Patent Office

Des. 197,200
Patented Dec. 24, 1963

197,200

TANK COVER

Omer E. Miller, 2316 Linden Ave.,
South Plainfield, N.J.

Filed Nov. 7, 1962, Ser. No. 72,414

Term of patent 14 years

(Cl. D81—2)

The dotted lines shown in the drawings represent the body of a tank and are for illustrative purposes only.

I claim:

The ornamental design for a tank cover, as shown and described.
